US0D1087172S

(12) **United States Design Patent** (10) Patent No.: **US D1,087,172 S**
(45) Date of Patent: ** Aug. 5, 2025

(54) **LAWN MOWER**

(71) Applicant: **Shenzhen Senhe Innovation Technology Co., Ltd.**, Shenzhen (CN)

(72) Inventors: **Xingchi Chen**, Guangdong (CN); **Li Qiu**, Guangdong (CN); **Chang Li**, Guangdong (CN)

(**) Term: **15 Years**

(21) Appl. No.: **35/521,374**

(22) Filed: **May 30, 2024**

(80) **Hague Agreement Data**

Int. Filing Date: **May 30, 2024**

Int. Reg. No.: **DM/237708**

Int. Reg. Date: **May 30, 2024**

Int. Reg. Pub. Date: **Jun. 21, 2024**

(30) **Foreign Application Priority Data**

Primary Examiner — Mark A Goodwin

(57) **CLAIM**

The ornamental design for lawn mower as shown and described.

DESCRIPTION

The patent or application file contains at least one drawing executed in color. Copies of this patent or patent application publication with color drawing(s) will be provided by the Office upon request and payment of the necessary fee.

1. Lawn mower

1.1 : Front

1.2 : Back

1.3 : Left

1.4 : Right

1.5 : Top

1.6 : Bottom

1.7 : Perspective

1.8 : Perspective

1. 1 is a front view of a lawn mower showing our new design; 1. 2 is a rear view thereof; 1. 3 is a left side view thereof; 1. 4 is a right side view thereof; 1. 5 is a top view thereof; 1. 6 is a bottom view thereof; 1. 7 and 1.8 are perspective views thereof. The colors shown do not form part of the claimed design.

**1 Claim, 8 Drawing Sheets
(8 of 8 Drawing Sheet(s) Filed in Color)**
